UNITED STATES PATENT OFFICE

JOHN F. GRACE, OF ARLINGTON, NEW JERSEY, ASSIGNOR TO WORTHINGTON PUMP AND MACHINERY CORPORATION, OF NEW YORK, N. Y., A CORPORATION OF VIRGINIA

CONDENSER

Application filed May 29, 1928. Serial No. 281,506.

This invention relates to surface condensers, and an object of the invention is to provide a surface condenser, constructed to prevent leakage of circulating cooling water into the steam space, in which condenser, the cooling water tubes are expanded at both ends into the tube heads and suitable means are provided to compensate for expansion and contraction of the tubes due to temperature variances within the condenser.

It is an object of the present invention to provide a simple, efficient and relatively inexpensive condenser construction which will permit fluid tight connections between the tubes and the tube heads, allowing movement of one of the tube heads relative to the casing of the condenser, to compensate for expansion and contraction of the tubes under variances of the temperatures, within the condenser, while localized temperature variances and the resultant unequal expansion and contraction of certain of the tubes relative to others, will be compensated for by independent movement of the tubes relative to one of the tube heads.

More specifically, the present invention comprises a condenser such as shown and described in my companion application filed March 8th, 1928, Serial Number 260,020, in which one of the tube heads flexes to compensate for expansion and contraction of the tubes and the present invention also provides means to permit the tubes to move independently of each other and relative to one of the tube heads, while suitable means are provided to prevent creeping of the tubes at their connection with the other tube head.

With these objects in view, the invention consists in various features of construction and combination of parts, which will be first described in connection with the accompanying drawings, showing a condenser of the preferred form embodying the invention, and the features forming the invention will be specifically pointed out in the claims.

Fig. 1 is a longitudinal section through a condenser constructed in accordance with this invention.

Fig. 2 is an enlarged detailed section show-

ing in section a tube and its connection with the tube heads.

Fig. 3 is a detailed section similar to Fig. 2 showing a modified form of the invention, and

Fig. 4 is a view similar to Fig. 2 showing a still further modification of the invention.

Referring more particularly to the drawings, the improved condenser comprises the usual case 1 which has the tube heads 2 and 3 mounted therein which carry the tubes 4. The tubes 4 open through the tube heads 2 and 3 into the water boxes 5 and 6 so as to permit circulation of cooling water through the condenser for condensing steam which enters the condenser through the steam or exhaust inlet 7.

In the present invention, the tube head 3 is greater in diameter than the tube head 2 and it is also thinner so as to permit it to flex under expansion and contraction of the tubes 4, to compensate for such expansion and contraction without disrupting the connections between the tubes and the tube heads and which would permit leakage of the cooling water into the steam space within the condenser.

In the form of the invention shown in Figure 2 of the drawings the tubes 4 have their ends rolled or expanded into the tube head 2 and lightly expanded into the tube sheet or head 3 so as to provide fluid tight connections between the tubes and the tube heads. The tubes 4 extend only partly through the tube head 2 and ferrules 10 are threaded into the tube head 2 and abut the inner ends of the tubes 4 so as to prevent creeping of the tubes relative to the tube head 2.

The ends of the tubes, at the tube head 3, also extend only part of the way through the tube head, and they extend into the counter bores 11 of the ferrules 12. The ferrules 12 are threaded into the tube head 3 and engage about the outer surface of the ends of the tubes 4 which tubes are lightly expanded into the tube head 3, where they engage the said tube head.

The tubes 4 terminate short of the shoulders 13 in the ferrules 12, which are formed by the counter bores 11, so as to permit independent movement of each tube relative to the other tubes.

and relative to the tube head 3 to compensate for expansion and contraction of the tubes under localized temperature variances, such as sometimes exist in condensers, principally 5 those of large surface area.

In Fig. 3, which shows a slight modification of the invention, the tubes 4' are lightly expanded into the tube head 3', while packing of any suitable type, preferably fibre 10 packing 15, is mounted about the end portions of the tubes and is forced into position by the ferrules 12', the shoulders 13' of which are spaced so as to permit independent movement of the tubes 4' under expansion and 15 contraction.

In Fig. 4 of the drawings, still a further modified form of the invention is shown and in this form the tubes 4A have their ends inserted through the tube head 2A and expanded therein, the ferrules 10 being eliminated. The tubes 4A, however, extend only 20 part of the way through the tube head 3A, having their inner ends spaced from the inner ends of the ferrules 16, leaving a space 17 to permit independent movement of the tubes 25 4A under expansion and contraction, while the ferrules 16 limit the outward movement of the tubes.

While in Figs. 2 and 3 of the drawings, 30 the ferrules 10 are shown, they being eliminated in Fig. 4, it is to be understood that ferrules corresponding to these ferrules 10 may be used in connection with any of the forms shown in Figs. 2 to 4, or they may be 35 eliminated as desired without departing from the spirit of this invention.

With condensers constructed in accordance with the present invention, the tubes are prevented, even though they should be 40 snapped across, from crawling or creeping out at either end, because they are held in position by the ferrules. In case tubes should wear and work loose at the flexible tube head end, it can be easily packed, or 45 packing 15 renewed, to provide tight non-leaking connection with the flexible tube head.

In all the forms of the invention shown it 50 will be noted that the length of the portions of the tubes expanded in the tube heads 3, 3' or 3A is less than the length of the portions of the tubes expanded in the tube head 2 or its corresponding tube head in the forms shown in Figs. 3 and 4 of the drawings, and it is 55 to be understood that such lengths are lightly expanded in the respective tube sheets thereby providing less resistance to movement of the tubes at the tube heads 3, 3' or 3A and consequently if there is any longitudinal 60 independent, or creeping movement of the tubes it will be at the ends where provision for such movement is made.

It will be understood that the invention is 65 not to be limited to the specific construction or arrangement of parts shown but that these

may be modified widely within the invention defined by the claims.

What is claimed is:

1. In a condenser, tube heads, tubes having their ends expanded into the tube heads, ferrules carried by one of said tube heads and abutting the ends of the tubes, ferrules carried by the other tube head and partly surrounding the ends of the tubes, said last named ferrules provided with shoulders 70 spaced sufficiently to permit limited movement of the tubes under expansion and contraction, and packing mounted about the ends of the tubes inwardly of said last named ferrules.

2. In a condenser, tube heads, tubes having their ends expanded into said heads, one of said heads being of larger diameter and thinner than the other and adapted to flex to compensate for limited expansion and contraction of the tubes, ferrules carried by said larger and thinner tube head and spaced from the ends of the tubes sufficiently to permit limited movement of the tubes under expansion and contraction, packing mounted 35 about the ends of the tubes in said larger tube head, and ferrules carried by the other of said tube heads and abutting the ends of the tubes.

In testimony whereof I affix my signature. 35
JOHN F. GRACE.
